UNITED STATES PATENT OFFICE

110,103

DESIGN FOR A COMBINATION ASHTRAY

Mildred B. Baily, Norristown, Pa.

Application March 22, 1938, Serial No. 76,016

Term of patent 14 years

To all whom it may concern:

Be it known that I, Mildred B. Baily, a citizen of the United States, residing at Norristown, in the county of Montgomery and State of Pennsylvania, have invented a new, original, and ornamental Design for a Combination Ash Tray, of which the following is a specification, reference being had to the accompanying drawing, forming part thereof.

I claim:—

The ornamental design for a combination ash-tray, as shown.

MILDRED B. BAILY.
